Assistant Examiner—J. H. Musgrave
Attorney, Agent, or Firm—Anthony S. Zummer

[73] Assignee: Juno Lighting, Inc., Des Plaines, Ill.

[57] CLAIM
The ornamental design for a combined support clamp and electrical receptacle, as shown and described.

[**] Term: 14 Years

DESCRIPTION

[21] Appl. No.: 657,541

[22] Filed: Feb. 19, 1991
[52] U.S. Cl. D8/73
[58] Field of Search D8/72, 73; 248/72, 231.7, 248/231.3, 216, 228; 269/143, 239, 238, 249, 240, 152, 246

FIG. 1 is a front, bottom and left-side perspective view of a combined support clamp and electrical receptacle showing our new design;
FIG. 2 is a left side elevational view, the right side being a mirror image;
FIG. 3 is a front elevational view thereof;
FIG. 4 is a rear elevational view thereof;
FIG. 5 is a top plan view thereof; and,
FIG. 6 is a bottom plan view thereof.
A lamp holder and portions of a support rod and an electrical cord are shown in broken lines for illustrative purposes only.
